UNITED STATES PATENT OFFICE.

WILLIAM F. BOLLY, OF SANDUSKY, OHIO.

ACETYLENE-GAS GENERATOR.

SPECIFICATION forming part of Letters Patent No. 735,937, dated August 11, 1903.

Application filed July 8, 1901. Renewed July 1, 1903. Serial No. 163,978. (No model.)

To all whom it may concern:

Be it known that I, WILLIAM F. BOLLY, a resident of Sandusky, in the county of Erie and State of Ohio, have invented certain new and useful Improvements in Acetylene-Gas Machines; and I do hereby declare the following to be a full, clear, and exact description of the invention, such as will enable others skilled in the art to which it pertains to make and use the same.

This invention relates to a new and improved acetylene-gas generator.

The object of my invention is to provide a generator of the character indicated adapted to be placed in the basement of a house and connected directly with the service-pipes thereof.

With this end in view my invention consists in providing a combined generator and gas-tank provided with new and improved means for regulating the production of the gas embracing new and improved means for feeding water to the carbid in the generator and new and improved means for withdrawing the water from the carbid when sufficient gas has been generated.

My invention also consists in the features of construction and combinations of parts hereinafter set forth in the specification, illustrated in the drawings, and pointed out in the claims.

In the accompanying drawings, Figure I illustrates a central section of my improved generator. Fig. II represents a section on line II II, Fig. I.

Referring to the drawings, *a* represents the generator of my gas-machine. This generator comprises a tank *a'*, which is divided by means of an interior wall *b* into an inner chamber *b'* and an outer chamber *b''*, completely surrounding the inner chamber. The outer chamber is adapted to hold water or other liquid for forming a seal. In the bottom of the inner chamber *b* is formed an opening or passage-way *b''*. In the interior of the chamber *b* and resting on the bottom thereof is located a perforated receptacle or cage *c* for holding the carbid.

a² represents the cover of the tank *a*, which is provided with a short annular flange *a³*, adapted to fit closely within the rim of the tank *a*. Inside of the flange *a³* a second an-

nular flange *a⁴* is secured and so arranged that when the cover *a²* is in place the flange *a⁴* extends into and almost to the bottom of the compartment *b²*. On the outside rim of the cover are formed a number of ears or projections *a⁵*, which engage correspondingly-arranged projections *a⁶* on the exterior of the tank, forming means for securing the cover on the tank. In the top of the cover *a²* is formed a valve *a⁷*. The cover *a²* and the flange *a⁴* together constitute a gas-bell for receiving the gas when first generated.

The reservoir or gas-tank is arranged in proximity to the generator and comprises the telescoping members, constituting the water-tank *e* and the gas-bell *f*, respectively. In the center of the bottom *e'* of the water-tank is formed a circular opening *e²*, and tightly fitting in the opening *e²* and extending upwardly to within a short distance of the top of the tank is a vertical tube or casing *g*. Located within the chamber *g'*, formed by the tube *g*, is a plunger *h*, which is connected with the bell *f* by a rod *h'*.

k represents a gas-pipe which connects the upper portion of the generator with the upper portion of the gas-tank.

k' represents a pipe for conducting the gas from the tank to the service-pipes of the house, and *k²* represents a waste-pipe to allow the escape of gas from the tank when the gas is being generated too rapidly. This pipe *k²* enters the tank near the bottom and then extends vertically within the tank and has its mouth a short distance above the level at which the liquid seal usually stands in the said tank.

Secured to the top of the gas-bell *f* is a pipe *k³*, which is closed at its upper end. This pipe *k³* is arranged to telescope with the pipe *k²*. Openings *k⁴* are preferably formed in the pipe *k³* near its lower end, so that the said openings will be normally below the level of the liquid seal.

Between the generator and the gas-tank is located a water-tank *l*. The object of this water-tank is to prevent the transmission of heat from the generator to the gas-tank.

Below the generator and gas-tank is located a water-receptacle or conduit *m*, one end of said conduit being preferably lower than the other end. This conduit *m* is in open rela-

tion with the chamber b' of the generator and the chamber g' of the gas-tank. The conduit m is provided with a valved outlet m' , so situated that the water will flow out at the 5 valve as soon as the water in the conduit rises high enough to enter through the opening b^3 in the bottom of the chamber b' . An opening is formed in the side of the conduit and provided with a screw-threaded nozzle 10 m^2 , so that a hose may be secured thereto. The nozzle is normally closed by means of a plug m^3 . To the opposite end of the conduit is connected a pump n by suitable length of piping n' . This pump is designed for cleaning 15 the conduit and is adapted to remove the water and sediment therefrom.

o represents a water-pipe leading from the bottom of the gas-tank to the conduit m , provided with a valve o' .

20 The operation of my gas-machine is as follows: The carbid is placed in the cage c and the cover a^2 is locked in position by inserting the ears a^5 into the projections a^6 . A suitable quantity of water for forming the seals 25 is then poured into the chambers b^2 and e . The valve m' in the conduit m is then opened, after which water is admitted to the conduit m through the pipe o by opening the valve o' . When the water in the conduit rises high 30 enough to enter the chamber b' and comes in contact with the carbid, it begins to flow out through the valve m' . The valve o' is then closed, after which the valve m' is also closed. As soon as the water touches the carbid it is 35 drawn up by capillary attraction and gas is generated and passes through the pipe k into the tank e . If more gas is generated than passes through the pipe k' , the gas within the tank forces up the gas-bell f , which lifts the 40 plunger h in the chamber g' . The water in the conduit m flows into space left vacant by the plunger and the water recedes entirely from the carbid. If the gas continues to form, owing to the water already absorbed by 45 the carbid, the gas-bell will continue to rise,

lifting the tube k^3 until the openings k^4 in the tube come above the level of the water seal, when the gas will enter the openings and escape through the waste-pipe k^2 . If for any reason it should become necessary to quickly 50 relieve the pressure of gas in the generator, it can be readily accomplished by opening the valve a^7 in the top a^2 .

What I claim is—

1. In an acetylene-gas machine, a carbid-chamber, a water-tank, a gas-bell mounted in said water-tank, a gas-pipe leading from the carbid-chamber to the interior of the gas-bell, a casing forming a chamber within the water-tank, a plunger located in said chamber and operatively connected to said gas-bell, a water-conduit extending from said chamber in said water-tank to the said carbid-chamber, a water-pipe connection between said water-tank and water-conduit, a 60 valve located in said water-pipe, and a pump operatively connected with said water-conduit, substantially as described and for the purpose set forth.

2. In an acetylene-gas machine, a carbid-chamber, a water-tank, a gas-bell mounted in said water-tank, a gas-pipe leading from the carbid-chamber to the interior of the gas-bell, a pipe for conducting the gas away from the gas-bell, a casing forming a chamber 75 within the water-tank, a plunger located in said casing and operatively connected with the said gas-bell, a water-conduit extending from the said chamber in said water-tank to the said carbid-chamber, a water-pipe extending from the said water-tank to the said water-conduit, and a valve arranged in said water-pipe, substantially as described and for the purpose set forth.

Signed by me at Cleveland, Ohio, this 31st 85 day of May, 1901.

WILLIAM F. BOLLY.
